UNITED STATES PATENT OFFICE.

PAUL S. LUTTRELL AND PAUL C. ROSKE, OF OAKLAND, CALIFORNIA, ASSIGNEES TO AMERICAN CLOCK CORPORATION, OF OAKLAND, CALIFORNIA, A CORPORATION OF CALIFORNIA.

ALARM CLOCK.

Application filed July 18, 1921. Serial No. 485,423.

To all whom it may concern:

Be it known that we, PAUL S. LUTTRELL and PAUL C. ROSKE, citizens of the United States, and residents of the city of Oakland, 5 county of Alameda, State of California, have invented a new and useful Alarm Clock, of which the following is a specification.

This invention relates to improvements in 10 clocks and more particularly to the alarm mechanism thereof.

It is one of the objects of the present invention to provide in an alarm clock, a mechanism that can be selectively set so that 15 an alarm will be sounded substantially at a predetermined minute of a given or desired hour.

Another object of the invention is to provide a setting mechanism for an alarm clock 20 in which separate hour and separate minute dials are utilized entirely independent of the front face dial of the clock. It is, in this connection, an object of the invention to provide for the setting of the alarm mechanism with facility and accuracy, the alarm indicating dials being so arranged as to eliminate confusion and error.

The invention possesses other objects and 25 features of advantage, some of which with the foregoing, will be made manifest in the following description of the preferred form of the invention, which is illustrated in the drawings accompanying and forming part of the specification. It is to be understood 30 that it is not intended to limit the invention to the embodiment shown by the said drawings and description, as variations may be adopted within the scope of the invention 35 as set forth in the claims.

40 Fig. 1 is a perspective of a form of the improved clock showing the front usual dial and the alarm setting dials arranged independently thereof.

Fig. 2 is an elevation and diagrammatic 45 view of the clock-work and combined alarm setting mechanism.

Fig. 3 is a side or edge view of the works looking toward the alarm setting mechanism.

50 Fig. 4 is a section of a fragment in a vertical plane through the framework and looking in the direction of the inner end of the setting counter shaft.

Fig. 5 is a front view of the clock.

Fig. 6 is a rear view of the clock back. 55

Fig. 7 is a detail of the hammer driving train and the silencer.

Fig. 8 is a plan view of the silencer as shown in Fig. 7.

The present invention embodies a set of 60 alarm indicating dials arranged independently of the main outer dial of the clock and with which indicating dials there are co-operative indicating pointers connected by a gear train including a main shaft having 65 provision whereby it may be manually operated so as to set the indicating pointers to the predetermined position at which it is desirable to have an alarm mechanism operate to sound an alarm at a designated 70 time.

The invention may be incorporated in a 75 clock structure in combination with any suitable clock mechanism which is arranged, in the present case, within a suitable case 2, 80 having a front outer dial 3 over which traverse the usual minute hand 4 and the hour hand 5. Suitably located upon the casing 2, and in the present instance, on one side thereof, there is provided an alarm dial 6 85 graduated and indexed with minute numbers 7 and adjacent the minute dial 6 is an hour dial 8. These dials may be arranged in a countersunk portion of the side of the casing 2 and from which projects a main 90 setting shaft 10, Fig. 2, having on its outer end a knurled head or wheel 11. This wheel may be formed on a threaded socket part 12, to be screwed on to the end of the main shaft 10 and carries a minute pointer 13 95 which is adapted to be turned clock-wise in front of the minute dial 7, to a predetermined position.

Behind the dials 6-8 and inside of the 95 casing 2 is provided a reduction train including a pinion 14 on the main shaft 10, transmitting through intermediate gears 15 to a large gear 16 secured on an index counter shaft 17, projecting forwardly through the center of the outer dial 8 and having an 100 hour pointer 18. The reduction train is so proportioned that during one rotation of the main shaft 10, manipulated by the setting wheel or head 11, the counter shaft 17 turns but one-twelfth of a revolution, thus 105 enabling the setting of the minute pointer

13 and the outer pointer 18 synchronously and to the desired minute and hour at which an alarm is required.

The clockwork may be of the usual form 5 and includes a central arbor 20 for the minute hand 4 and is provided with a pinion 21, Fig. 2, driving a reduction train, terminating in an alarm cam gear 22, which is loosely and shiftably mounted on a setting 10 spindle 23 journaled in the framework F in a position at right angles to and its axis intersecting the axis of the counter shaft 17, so that these shafts can be interconnected by suitable means. As here shown, the inner 15 end of the counter shaft 17 is provided with a gear 17^a meshing with a complementary gear 23^a of equal size so that the shaft 17 and the setting spindle 23 turn in unison when the main shaft 10 is rotated.

20 One end of the setting spindle 23 is provided with a collar 24 having a lug 25 which is so disposed as to ride upon the end face of an alarm cam 26 which is fixed on the alarm cam wheel 22. This wheel is normally thrust toward the lug 25 to press the cam 26 against the lug by means commonly termed the "let-off" lever designated 27, which is secured to the framework and has an inwardly turned end 28 designed to engage a "cut-out" wire or lever 29 which is attached to a verge shaft 30 to which is secured a hammer wire 31, having on its outer end a hammer 32 designed to strike a contiguous bell arranged in or on the clock case 35 and not here shown.

The verge on the shaft 30 is designed to be oscillated by the usual verge actuating escapement wheel 33 which is driven by power derived from an alarm spring 34 by 40 the usual transmission gear train.

45 From the above it will be seen that during the operation of the main clock works the alarm cam wheel 22 will run with the rate of speed of the outer hand of the clock and the alarm let-off 27 will cause the wheel with its cam 26, to be snapped outwardly when the lug 25 of the setting spindle 23 passes the relief shoulder 26^a during the rotation of the cam 26. This permits the 50 withdrawal of the let-off lever end 28 and releases the cut-out lever or wire 29 and permits the verge mechanism to be actuated and throw the hammer 32 against the bell.

The operation of the setting spindle 23 55 to bring the lug 25 to a predetermined position is readily achieved by rotation of the main shaft 10 and by virtue of the independent minute pointer 13 and the hour pointer 18, the parts can be set so that the alarm will be caused to go off at practically a predetermined minute of any hour.

It is, among other objects of the invention, an object to provide means for insuring the release of a silencing device that 60 may be provided in combination with the

clock for the purpose of interrupting the operation of the alarm hammer which, unless it is impeded, will continue to vibrate until its driving spring has become entirely unwound.

70 It is further, in this connection, an object of the invention to provide a device which can be readily thrown to interrupt the operation of the alarm mechanism. It is, further, an object to provide means in connection with the silencing mechanism whereby the silencer will be rendered inoperative upon the striking mechanism as soon as an attempt is made to wind the alarm spring. 75 This is for the purpose of avoiding the danger of leaving the silencing device in its effective position upon the alarm mechanism, in which case there would be a failure to give the desired alarm when the given time had arrived.

80 To that end, a form of silencer is here illustrated as comprising a resilient arm 40, one end of which is secured upon the framework F of the clock and which is provided with an abutment 41 at its free end which 85 normally occupies a position out of the path of movement of the hammer wire 31, when this is driven by the oscillation of the verge arbor 30. The arm or silencing member 40 is preferably of resilient material and may 90 be in the form of a leaf spring, its free end normally being entirely clear of the hammer wire 31 and the silencer 40 is adapted to be thrown to an outer or effective position so as to interrupt the operating hammer. 95

For the purpose of so actuating the silencer member 40, there is mounted on the back B of the case 2 of the clock a lever arm 44 which is adapted to rotate in a bearing 45 in such manner that the swinging 100 end of the lever 44 at the back of the clock will move into juxtaposition with the winding handle 34^a of the usual alarm spring inside of the clock case. When thrown to such position, which is indicated in dotted 105 lines, Fig. 6, an arm 46 of the lever 44 and which is inside of the back B, moves into engagement with the contiguous swinging or yielding end of the silencer member 40 and this is sprung outwardly to the position indicated in dotted lines, Fig. 6, at 110 which time the shoulder 41 of the silencer member moves into effective stopping position with respect to the hammer wire 31 and it is thereby prevented from continuing operation under the impulse of its driving spring. Suitable means may be employed to temporarily hold the lever 44 in its applied or effective silencing position, and, as 115 shown, the swinging end of the silencer member 40 is provided with a concave seat 40^a to receive the contiguous end 46 of the silencing lever 44.

120 After the silencing device has been manipulated to interrupt the operation of the 125

alarm, unless the alarm hammer is again released from the silencing device, the alarm mechanism will fail to operate at such predetermined time as the alarm has been set for. As it is customary for the users of alarm clocks to "wind the alarm" once a day by the present arrangement of the silencing lever 44, this lever will be thrown to releasing position as soon as an attempt is made to rotate the alarm winding handle 34^a of the alarm mechanism. From this it will be seen that there can be no danger of failure of the alarm to occur at the desired time because the alarm silencer is disengaged coincidently with an attempt to wind the alarm spring.

What is claimed is:

1. An alarm clock provided with a front hour and minute dial and respective hands for hour and minute indication in combination with a clock works; and an alarm mechanism with synchronous hour and minute pointers, and a pair of alarm dials separate from the said front dial for the hour and minute alarm setting pointers.

2. An alarm clock having, in combination, a front face dial and hour and minute hands operative over the dial in the usual manner; and an alarm setting mechanism including a setting main shaft extending through the casing at right angles to the face of the clock and having an indicating pointer, and an alarm dial over which said pointer is movable; the said dial being arranged separately from the face dial, and a second alarm dial associated with the aforesaid alarm dial, and an indicating pointer movable over the second alarm dial.

3. An alarm clock having, in combination, a front face dial and hour and minute hands operative over the dial in the usual manner; and an alarm setting mechanism including a setting main shaft extending through the casing of the clock and having an indicating pointer, an alarm dial over which said pointer is movable; the said dial being arranged separately from the face dial, a second alarm dial associated with the aforesaid alarm dial, and an indicating pointer movable over the second alarm dial; the alarm pointers being intergeared so that they are set synchronously when the main stem is actuated.

4. An alarm clock having, in combination, a casing with a face hour and minute dial and a clock works arranged in the casing and having hour and minute hands operative over the face dial, an alarm mechanism including a setting spindle upon which is rotatively and slidably mounted an alarm cam wheel which is driven by the clock work; and means for actuating the setting spindle including a set of intergeared shafts,

each carrying a pointer for indicating minute and hour setting of the alarm mechanism.

5. An alarm clock having, in combination, a casing with a face hour and minute dial and a clock works arranged in the casing and having hour and minute hands operative over the face dial, an alarm mechanism including a setting spindle upon which is rotatively and slidably mounted an alarm cam wheel which is driven by the clock work; means for actuating the setting spindle including a set of intergeared shafts, each carrying a pointer for indicating minute and hour setting of the alarm mechanism, and individual dials for the hour and minute pointers respectively.

6. An alarm clock having, in combination, a casing with a face hour and minute dial and a clock works arranged in the casing and having hour and minute hands operative over the face dial, an alarm mechanism including a setting spindle upon which is rotatively and slidably mounted an alarm cam wheel which is driven by the clock work; means for actuating the setting spindle including a set of intergeared shafts, each carrying a pointer for indicating minute and hour setting of the alarm mechanism, and individual dials for the hour and minute pointers respectively, the alarm being arranged separately from the face dial.

7. An alarm clock having, in combination, an alarm mechanism including a winding handle, means for silencing the alarm by interrupting the operation of the alarm mechanism and means in the path of the winding handle for insuring the tripping of the silencer when the said winding handle is actuated to wind the mechanism.

8. An alarm clock having, in combination, an alarm mechanism, a silencer to interrupt the operation of the alarm mechanism and means for tripping the silencer when the alarm mechanism is wound, and engageable by the user when manually winding the said mechanism.

9. An alarm clock having, in combination, an alarm mechanism including a hammer wire and a winding handle; a silencer adapted to be set in position to engage the said hammer wire and interrupt its oscillations, and means adapted to set the silencer and which, when in the silencer setting position is disposed adjacent to the manually operative handle of the alarm mechanism so that when said part is manually engaged and moved, the silencer setting means will be tripped to release the silencer.

In testimony whereof, we have hereunto set our hands.

PAUL S. LUTTRELL.
PAUL C. ROSKE.
